UNITED STATES PATENT OFFICE.

CARL O. ANDERSON AND SOREN NELSEN, OF SPOKANE, WASHINGTON.

TRAFFIC-SIGNAL.

1,369,951.

Specification of Letters Patent.

Patented Mar. 1, 1921.

Application filed May 17, 1920. Serial No. 381,929.

To all whom it may concern:

Be it known that we, CARL O. ANDERSON and SOREN NELSEN, citizens of the United States, residing at Spokane, in the county 5 of Spokane and State of Washington, have invented new and useful Improvements in Traffic-Signals, of which the following is a specification.

This invention relates to improvements 10 in traffic signals and has to do more particularly with a signal of this character for use on an auto.

One of the features of this invention is to provide a signal in which the semaphore 15 may be swung from a vertically concealed position laterally in either of two directions into horizontal signaling positions or into a vertical uppermost signaling position, the semaphore being capable of movement 20 throughout a complete circle of three hundred and sixty degrees.

In order to provide for this character of complete circular movement of the semaphore, there is included in the invention a 25 novel form of casing of such structure that all of the weight and strain are carried and sustained by the casing while the cover for the casing is free from such strain and merely functions as a cover.

In that embodiment of the invention in which the same is attached in laterally projecting relation from a wind-shield, there is provided a novel form of operating mechanism accessible to the driver and which 30 functions not only to move the semaphore into four distinct positions but also to hold the semaphore in such positions, there being no dead center irrespective of the directions in which the semaphore is moved.

Other features and objects of the invention will be more fully described in connection with the accompanying drawing and will be more particularly pointed out in 40 and by the appended claims.

In the drawings:

Figure 1, is a view in rear elevation of the improved signal with parts broken away and showing the signal mounted upon the left hand post of an auto wind-shield.

Fig. 2, is a rear view of the semaphore casing with the cover omitted.

Fig. 3, is an edge elevation looking from the left of Fig. 2 with the cover in place.

Fig. 4, is a vertical sectional view on line 4—4 of Fig. 2. 55

Fig. 5, is a vertical sectional view on line 5—5 of Fig. 1.

Fig. 6, is a plan view of the adjusting drum casing looking in the direction of the arrow of Fig. 1. 60

Fig. 7, is a diagrammatic view of the device showing the different positions to which the semaphore may be adjusted.

Like characters of reference designate similar parts throughout the different figures of the drawing. 65

As illustrated, 1 designates the left hand post of a wind-shield. In the form of the invention shown which is adapted for attachment to a wind-shield, 2 designates a 70 hollow supporting arm having any suitable means, as indicated at 3, for attachment to the post 1. The outer end of said hollow arm 2 is provided with flanges 4 and 5 to which is rigidly secured in a substantially 75 vertical position an elongated semaphore casing comprising a back wall 6 and surrounding edge walls 7. An opening 8 in the edge wall 7 registering with the hollow arm 2 provides for passage of operating 80 means which will be later described. The form of the casing, as regards the shape of the lateral or edge walls is clearly shown in Figs. 1 and 2, the lower enlargement 85 providing for a direction mirror which will be later described.

As a part of a semaphore operating means, a drum 9 is disposed in the upper portion of the semaphore casing, the latter having a sleeve 10 forming means on which 90 the drum 9 is rotatively journaled. The length of the drum is such that its outer or exposed end projects slightly laterally of the edges of the wall 7, for a purpose which will later appear. A bolt 11 extends through 95 the sleeve 10 and forms a means for sustaining the upper portion of a cover which will be presently described. A semaphore 12 has its upper end secured to the drum 9, as indicated at 13 so that the drum 9 not only 100 functions as a support for the semaphore but also as an operating member therefor. The semaphore 12 hangs pendent from the drum 9 and is provided with an opening through which the bolt 11 extends. Now 105 it will be clear from Figs. 3 and 4 that

the semaphore 12 is in clearance relation to the edges of the wall 7 due to the height or length of the drum 9 and it will also be seen that the semaphore is in clearance relation with respect to the arm 2.

Reference will next be made to the improved form of cover and to the manner in which the same is mounted on the semaphore casing to give the semaphore freedom of 10 movement throughout a complete circle of three hundred and sixty degrees.

The cover is indicated at 14 and the same is proportioned similarly to the semaphore casing. The lower end of the cover is 15 secured at 15 to a solid part of the casing radially beyond the sweep of the semaphore 12, the extreme end of the latter being indicated at 16. The upper end of the cover 14 has an opening through which the bolt 11 20 passes, the head 17 resting against the cover.

A washer 18 may be interposed between the cover 14 and the semaphore 12 to space the cover in free working clearance from the semaphore. Thus it will be seen that notwithstanding the fact that the semaphore casing is pendently hung from its upper end, the cover may be secured thereto in such a manner as not only to effectively support the cover but also to provide an open space 30 through which the semaphore may be swung throughout a complete circle. The lower portion of the cover 14 is provided with a direction mirror 19 which functions in the usual manner. The semaphore 12 is provided with an opening 20 which registers with similar openings 21, in the cover 14, and a like opening in the back wall 6 shown at 22. These openings 21 and 22 may be provided with red glass so that when an electric lamp, as indicated in dotted lines at 23, 40 is interposed between the back wall 6 and the semaphore 12, it will glow through the red glass. However, my invention is clearly operative in the absence of such means.

Reference will next be made to the manner in which the semaphore is operated.

The arm 2 has an adjusting drum casing 24 in accessible relation to the driver and which is rigidly mounted on and which opens 50 to the arm 2. Interiorly of said casing 24 is disposed a drum 25. Drum 25 is provided with a relatively restricted bore 26 having an enlargement 27. An adjusting lever 28 is rigidly secured to said drum and operates 55 abreast of notches 29, in the wall of the casing 24. A bolt 30 extends through the casing and said drum and has a nut 31 engaging the back of said casing. A washer 32 is interposed between the head 33 of said bolt 60 and the lever 28, which latter is secured to the drum 25. The lever 28 is provided with an opening whereby a spring 33', interposed between shoulder 34 and washer 32 will normally act to force the drum 25 to the left 65 of Fig. 5. This causes the lever 28 to seek

the more recessed portions 35 of the notches 29 so as to hold the semaphore in the various positions to which it may be adjusted. A cable or wire 36, is trained about and fastened to drum 25 and drum 9 and may be 70 provided with a tensioning device such as a turn buckle 37. A similar cable or wire 38 is trained about and fastened to the drums in an opposite direction to that of wire 36 and may be provided with a tensioning device 75 39. The hollow arm 2 is provided with an opening 40 to render the tensioning devices accessible.

Next referring to the diagrammatic view shown in Fig. 7, *a* designates the position of 80 the semaphore 12 and the lever 28 in a non-signaling position. The letter *b* designates the semaphore and lever in the position where the driver is signaling that he is turning to the left. The letter *c* indicates the 85 relative positions when the driver is signaling that he is turning to the right. The letter *d* designates the signaling position to stop. Now one of the important features is that the semaphore may not only be shifted 90 to either the right or left signaling position, from position *a* but it may also be shifted from either of the horizontal positions directly to the stop position or it may be shifted to the stop position directly from the non-signaling position.

It is believed that the invention will be fully understood from the foregoing description and while we have herein shown and described one specific form of our invention, we do not wish to be limited thereto except for such limitations as the claims may import.

We claim:

1. A traffic signal comprising a casing 105 having an open side, a semaphore, means rotatively mounting said semaphore on said casing to permit the semaphore to swing abreast of said casing in either of two directions and throughout a complete circle, 110 and a cover for said casing secured to the latter beyond the radial sweep of said semaphore and also attached to said means, said cover being in spaced relation to said casing from beyond the point of attachment thereto 115 throughout the length of said semaphore to permit said semaphore to swing in either of two directions into and out of a concealed position with respect to and from between said casing and cover.

2. A traffic signal comprising an elongated casing normally vertically disposed, a semaphore, means rotatively mounting said semaphore near the upper end of said casing to permit the semaphore to swing laterally 125 abreast of said casing in either of two directions and throughout a complete circle, and a cover for said casing secured to the lower end thereof beyond the radial sweep of said semaphore and also swiveled at its 130

upper end to said means to hold the cover in place, said cover being in spaced relation to said casing from above the point of its attachment thereto throughout the length of 5 said cover to permit the semaphore to swing from between the cover and the casing in either of two directions.

3. A traffic signal comprising a casing having an open side, a semaphore drum rotatively mounted on said casing and having 10 means whereby said drum may be rotated, a semaphore arm attached to said drum and hanging pendently therefrom and said drum being proportioned to dispose said 15 semaphore arm in such lateral or parallel relation with the casing as to permit said drum to be swung in its own plane laterally in either of two directions, and a cover for inclosing said semaphore on one side thereof, 20 said cover being supportingly secured to said casing beyond the radial sweep of said semaphore at one end of said cover, the other end of said cover being secured to said drum stem.

25 4. A traffic signal comprising an open sided casing, a semaphore operating drum, a sleeve journaling said drum in said casing, means for rotating said drum to different positions, a semaphore having one end 30 secured to said drum and adapted to be swung by said drum into a position abreast of said casing or in either of two directions

outwardly from said casing, a cover having one end supportingly secured to said casing beyond the radial sweep of the free end of 35 said semaphore, and a screw or bolt extending through the other end of said cover and through said sleeve to secure the remaining end of said cover, said cover being in such spaced relation to said casing throughout 40 the length of said semaphore as to permit the latter to swing into or out of a concealed position between said cover and casing in either of two directions.

5. A traffic signal comprising an arm having 45 means for attachment to the wind-shield of an auto, a semaphore casing mounted on the outer end of said arm, a semaphore in said casing, and cable means for operating said semaphore extending through said 50 arm, the inner end of said arm having a drum casing, an adjusting drum in said casing having a shouldered bore, a bolt extending through said bore and journaling said drum, an operating lever mounted on 55 said drum, a spring interposed between the shoulder of said bore and said bolt head to hold said drum in position, said casing having notches for engagement by said lever to hold said drum in adjusted positions. 60

In testimony, that we claim the foregoing as our own, we hereby affix our signatures.

CARL O. ANDERSON.
SOREN NELSEN.
